UNITED STATES PATENT OFFICE

GUSTAVE PORGES, OF NEW YORK, N. Y., ASSIGNOR TO STROHMEYER & ARPE COMPANY,
OF NEW YORK, N. Y., A CORPORATION OF NEW YORK

POURING CAN

Application filed March 9, 1928. Serial No. 260,352.

This invention relates to cans such as are used for the preservation of foods and other articles, and aims to provide such can with an integral spout that permits safe and efficient 5 pouring of a liquid contained within the can.

A particular feature of the invention resides in providing a spout by deforming the rim of the can, without adding any materials or structural parts to the can. In the case 10 of a square can the rim may be deformed adjacent one of the corners to define the spout.

Further novelty is present in the arrangement of a depression forming a drip basin adjacent the spout, and in the provision of indicating means and/or a weakened portion 15 to guide the user in punching a pouring hole through the top of the can within the boundaries of the depression. The invention also contemplates punching a second hole for 20 the admission of air at a point directly opposite the pouring hole.

While a preferred form of the invention has been disclosed for purposes of illustration, it should be understood that various 25 changes may be made in the structure without departing from the spirit and scope of the invention as hereinafter set forth and claimed.

In the drawings:

Fig. 1 is a top plan view of a can embodying 30 the invention.

Fig. 2 is a side elevation of the can.

Fig. 3 is a section on line 3—3 of Fig. 1.

Fig. 4 is a section on line 4—4 of Fig. 1.

In metallic cans commonly in use for 35 serving liquid food materials, such as olive oil, the top of the can is joined to the side walls by a rolled seam. This seam includes several plies of the material from which the can is formed, and therefore forms a very 40 stiff rim at the corner where the side walls and top meet.

The present invention aims to utilize this 45 rim and to take advantage of its rigidity to form a spout for the can. This is accomplished by deforming the rim to produce a V-shaped spout pointing outwardly from the top surface of the can.

The drawing shows a square can 10 embodying the invention, but obviously it can 50 be applied to cans of any style or shape. The

can is shown as having a rolled seam 11 at the line of juncture of the side walls 12 and one of the ends 13. The spout is formed by bending inwardly the rim 11 and adjacent wall portions as indicated at 14, at opposite 55 sides of one of the corners of the can. The top of the can adjacent the spout is bent downwardly as at 15 to form a drip basin of limited area, and it is intended that the consumer shall puncture the top within the drip 60 basin to form a pouring hole.

To guide the consumer in making such a hole an indicating mark may be placed in the basin or preferably the top may be weakened at a point within the basin by 65 punching a rosette or similar figure into the material of the top as indicated at 16. In the latter case the rosette serves as an indicating mark and also facilitates the puncturing of the top. In a similar way an indicating 70 mark or rosette may be placed on the top at a point 17 opposite the mark 16 to assist the consumer in forming a vent hole to admit air while liquid is being discharged from the pouring hole. 75

The advantages and utility of the present structure will be apparent to those familiar with the art. The spout does not project beyond the normal boundaries of the can, so that there is no danger of its becoming bent 80 or broken in shipment or use, and the fact that it is formed by the stiffened rim 11 further insures its permanent shape. The drip basin catches any back flow from the spout and keeps it from spreading over the 85 top surface of the can.

I claim:

1. A can having a rim at the juncture of the side wall and the top, said rim being deformed to produce a spout pointing outwardly from the top surface of the can. 90

2. A can having a rolled seam at the juncture of the side wall and the top, said seam being deformed to produce a V-shaped spout pointing outwardly from the top surface of the can. 95

3. A can having a rim at the juncture of the side wall and the top, said rim being deformed to produce a spout pointing outwardly from the top surface of the can, and 100

the top of the can adjacent the spout being bent downwardly to form a drip basin.

4. A can having a rolled seam at the juncture of the side wall and the top, said seam being deformed to produce a V-shaped spout pointing outwardly from the top surface of the can, and the top of the can adjacent the spout being bent downwardly to form a drip basin.

10 5. A can having a rim at the juncture of the side wall and the top, said rim being deformed to produce a spout pointing outwardly from the top surface of the can, the top of the can adjacent the spout being indented to form a drip basin, the top of the can being weakened at a point within the drip basin to facilitate the formation of a pouring hole.

6. A can having a rolled seam at the juncture of the side wall and the top, said seam being deformed to produce a V-shaped spout pointing outwardly from the top surface of the can, the top of the can adjacent the spout being indented to form a drip basin, the top 25 of the can being weakened at a point within the drip basin to facilitate the formation of a pouring hole.

7. A can having a rim at the juncture of the side wall and the top, said rim being deformed to produce a spout pointing outwardly from the top surface of the can, the top of the can adjacent the spout being indented to form a drip basin, the top of the can being weakened at a point within the drip basin to facilitate the formation of a pouring hole, and the top being weakened at a point opposite the spout to assist in forming a vent hole.

8. A can having a rim at the junction of the side wall and the top, said rim being deformed to produce a spout pointing outwardly from the top surface of the can, the nose of the spout being located within the limits of the main can wall contour.

9. A can having a rim at the junction of the side wall and the top, said rim being deformed by portions bent inwardly to produce a spout pointing outwardly from the top surface of the can.

50 10. A can having a rolled seam at the junction of the side wall and the top, said seam being deformed by portions bent inwardly to produce a V-shaped spout pointing outwardly from the top surface of the can.

55 11. A can having a rim at the junction of the side wall and the top, said rim being deformed to produce a spout pointing outwardly from the top surface of the can, and the top of the can adjacent the spout being bent downwardly to form a drip basin communicating directly with the spout wall.

60 12. A can having a rim at the junction of the side wall and the top, said rim being deformed to produce a spout pointing outwardly from the top surface of the can, and

the top of the can adjacent the spout being bent downwardly to form a drip basin, the nose of the spout being located within the limits of the main can wall contour.

65 13. A can having a rim at the junction of the side wall and the top, said rim being deformed to produce a spout pointing outwardly from the top surface of the can, and the top of the can adjacent the spout being bent downwardly to form a drip basin, the nose of the spout being located within the limits of the main can wall contour, and the spout wall forming one limit of the drip basin, which communicates directly with the spout.
